UNITED STATES PATENT OFFICE.

ALLEN A. VAN ORSDALE, OF PHILADELPHIA, PENNSYLVANIA.

LUBRICATOR.

1,355,195.

Specification of Letters Patent. Patented Oct. 12, 1920.

Application filed March 15, 1920. Serial No. 365,989.

To all whom it may concern:

Be it known that I, ALLEN A. VAN ORSDALE, a citizen of the United States, residing at Philadelphia, in the county of Philadelphia and State of Pennsylvania, have invented new and useful Improvements in Lubricators, of which the following is a specification.

This invention relates to lubricators and it has more particular reference to that type which may be conveniently designated as a "splash feed" lubricator, that is to say to lubricators dependent functionally upon the vibrations of the machine or engine to which it is attached for feeding the lubricant to the desired part or parts.

The main object of this invention is to provide a lubricator of the type referred to which is devoid of any vibratory actuated valve.

Another object is to provide a "splash feed" lubricator with which is combined a renewable or removable container for the lubricant, said container before insertion in the lubricator being hermetically sealed and when placed in position automatically punctured or unsealed to feed the contained lubricant.

A further object of this invention is to provide a lubricator of the type specified which includes a minimum of simple and easily constructed parts that can be readily assembled or dissociated.

With the foregoing and other objects in view as will be more apparent as this description proceeds my invention consists essentially in the novel features of construction, combination and arrangement of parts hereinafter fully described and more specifically defined by the appended claims.

In the further disclosure of the invention reference is to be had to the accompanying sheet of explanatory drawings constituting a part of this specification and in which like characters of reference designate the same or similar parts in all the views.

Figure 1—is a central vertical section through a lubricator embodying my present improvements.

Fig. 2—is a transverse section taken substantially on the line 2—2 in the preceding figure.

Fig. 3—is a similar transverse section

taken substantially on the line 3—3 in Fig. 1.

Fig. 4—is a detail view of the concavo-convex insert hereinafter more particularly described; and

Fig. 5—is a perspective view—partly broken—of the lubricant container proper.

Referring to the drawings the numeral 10, designates the main or body portion of the lubricator which is provided with a cap or cover 11 appropriately threaded therein, a packing ring 12 being provided for the insuring of an air-closed joint. The lower end of the body portion 10, is screw-threaded at 13 to receive a similarly threaded supplemental or lower body portion 14 of approved cross section—hexagonal for example—and which is formed with the customary axial extension 15 and threaded nipple 16 by means of which the device can be readily connected in position or removed as desired. It is to be noted that the main and lower body portions 10, 14, when screwed together have a perfectly smooth joint 17 and that the former is provided with a lateral flange 18 which substantially divides the lubricator into upper and lower chambers 19, 20 respectively.

Formed internally of the lower chambers 20, are diametrically opposed lugs or projections 21 in the notched out parts 22 whereof there is forced and seated a concavo-convex or dished diaphragm 23—which when in place provides a series of openings 24 between its peripheral edge and the inner wall of the chamber 20 intervening the lugs or projections 21, for the purpose hereinafter explained.

Axially central of the lateral flange 18 there is formed or threaded thereinto an open-ended cylindrical extension 25 the lower peripheral edge whereof may be serrated if desired, and projecting central thereabove is a conical projection 26 apertured at 27, with a series of openings for the passage therethrough of the lubricant as hereinafter set forth.

The lubricant is preferably contained in an air and moisture proof container 28 which may be made of lead foil, paraffin-paper or thin sheet metal, and it is of dimension to fit easily on the upper chamber 19, and it will be readily understood

- that when the cap or cover 11 is screwed down into place the conical projection 26 will pierce the lower end 29 of said container 28 and cause the lubricant to ooze or 5 discharge through the apertures 27 and cylindrical extension 25, into the dished diaphragm 23 until it rises to the level shown at 30 where it will seal any further outflow of said lubricant. Now assuming that the 10 part of the machine or engine on which the lubricator is installed is subject to intermittent or constant vibration it will be readily seen that such vibrations will cause the lubricant contained in the dished diaphragm 15 to be washed or splashed over the edges thereof through the apertures 27 whence it will travel down the inner wall of the lower body portion 14 to the outlet 31 and part or parts to be lubricated. Furthermore 20 it will be understood that according to the frequency of vibration there will be a correspondingly increased or decreased feed of the lubricant, and that by providing an air vent 32 there will be a prompt replacement 25 of the air which will be caused to bubble up through or past the extension 25 and apertures 27 till it rises to the upper surface 33 of the lubricant in the container 28.
- 30 From the foregoing it will be readily seen that the action just described will take place and continue so long as the requisite degree of vibration is set up to cause a "splash" or wash-over of the lubricant from the dished diaphragm 23, whereby an automatic feed of lubricant will take place to the part or parts to be lubricated. Furthermore when the container 28 becomes emptied it can be easily removed and replaced by a fresh one 35 by simply removing the cap or cover 10 and picking it out with an appropriate tool or the fingers and to aid this removal opposed notches 34 may be provided in the upper peripheral edge of the main or body portion 10.
- 40 While I have described and shown one practical and preferred embodiment of my invention I wish it clearly understood that I do not limit myself to the precise details 45 of construction disclosed as various changes in the shape and arrangement of the several parts can be effected without departing from the spirit and scope thereof; for example the lower body portion may be elongated or angled to accommodate application of the lubricator in awkward and normally inaccessible positions, and it is intended to hereby include all such reasonable modifications as may fairly be construed as 50 falling within the scope and ambit of the appended claims.
- Having described my invention what I claim as new and desire to secure by Letters Patent is:—
- 65 1. A splash feed lubricator comprising a reservoir for the lubricant and having an outlet therefrom, a supplemental chamber disposed below the reservoir for the lubricant a dished diaphragm seated in the supplemental chamber and having peripheral 70 apertures for the passage of the lubricant therethrough when the lubricator is vibrated.
2. A splash feed lubricator comprising a reservoir having an outlet therefrom, a lubricant container adapted to seat in the reservoir, a supplemental chamber disposed below the reservoir, a dished diaphragm seated in the supplemental chamber and having peripheral openings for the passage 80 of the lubricant therethrough when the lubricator is vibrated.
3. A splash feed lubricator comprising an upper portion having an outlet therefrom, a lubricant container adapted to seat in the upper portion an air tight cap for threaded engagement on the upper portion, a supplemental chamber threaded on the lower end of the upper portion, a dished diaphragm seated in the supplemental chamber 90 and having peripheral openings for the passage of the lubricant therethrough when the lubricator is vibrated.
4. A splash feed lubricator comprising an upper portion having a threaded outlet 95 therefrom, a lubricant container adapted to seat in the upper portion, a cylindrical extension threaded into the aforesaid outlet and having an apertured conical projecting upper end extending into the upper portion, an air tight cap for threaded engagement on the upper portion, a supplemental chamber threaded on the lower end of the upper portion, a dished diaphragm seated in the supplemental chamber and having peripheral 100 openings for the passage of the lubricant therethrough when the lubricator is vibrated.
5. A splash feed lubricator comprising an upper portion having an internally threaded outlet therefrom, a lubricant container adapted to seat in the upper portion, a cylindrical extension threaded into the aforesaid outlet and having an apertured conical projecting upper end adapted to puncture the lower end of the lubricant container, an air tight cap for threaded engagement on the upper portion, a supplemental chamber threaded on the lower end of the upper portion, a dished diaphragm seated 115 in the supplemental chamber and having peripheral openings for the passage of the lubricant therethrough when the lubricator is vibrated.
6. A splash feed lubricator comprising an upper portion having an internally threaded outlet therefrom, a lubricant container adapted to seat in the upper portion, a cylindrical extension threaded into the aforesaid outlet and having an apertured conical 120
- 125
- 130

projecting upper end adapted to puncture the lower end of the lubricant container, an air tight cap for threaded engagement on the upper portion, a supplemental chamber 5 threaded on the lower end of the upper portion and having inwardly projecting notched lugs, a dished diaphragm seated in

the inwardly projecting notched lugs of the supplemental chamber and thereby forming peripheral openings for the passage of the 10 lubricant when the lubricator is vibrated.

In testimony whereof I affix my signature.

ALLEN A. VAN ORSDALE.
